APPARATUS TO BE USED IN CASTING
METAL

William F. Eppensteiner, Rahway, N. J., assignor
to The American Metal Company, Limited, New
York, N. Y., a corporation of New York

Application September 22, 1934, Serial No. 745,062

2 Claims. (Cl. 22—139)

This invention relates to improved apparatus to be used in casting metal, and particularly copper, in vertical molds of relatively small size in horizontal cross-section.

5 It is an object of the invention to provide an open top, vertical mold of a form adapted for use in the casting of copper wire bars having tapered end portions of lengths such that the ends of each tapered portion may be cropped and leave a bar having substantially like tapered portions at 10 its opposite ends.

In the accompanying drawing illustrating novel apparatus embodying the invention:—

Figure 1 is a vertical cross-sectional view 15 through a vertical mold, a portion of a furnace including a spout, a funnel by which metal poured from the spout may be directed into the mouth of the mold, and movable funnel-supporting means whereby the relative position of the funnel with respect to the spout and mold may be 20 adjusted, the cutting plane of the section being represented by the line 1—1 of Fig. 2.

Fig. 2 is a plan view of the mold, funnel and funnel-supporting means illustrated by Fig. 1.

Fig. 3 is a vertical, cross-sectional view of the mold, funnel and funnel-supporting means illustrated by Fig. 2, the cutting plane being represented by the line 3—3 of Fig. 2.

In Figure 1 is represented in vertical cross section a mold 20 broken away between its top and bottom so as to leave its height indefinite, but intended to be of vertical dimensions several times greater than its internal horizontal cross-sectional dimensions. This mold may preferably 30 be of copper adapted for use in the casting of copper bars or billets of any desired cross-sectional form but of relatively great length as compared with such cross-sectional dimensions. The lower end of the mold may be closed by a separable bottom or door 21, which may be hinged or otherwise secured to the overlying part of the structure by means (not shown) whereby it may be swung clear of the opening in the mold and permit a bar or billet cast therein to be dropped 35 freely therefrom through its bottom.

If desired, the walls of the mold, as well as the bottom, may be provided with hollow chambers (not shown) through which cooling water may be circulated as a means of regulating the temperature of the mold prior to and during a casting 40 operation.

The above-described features whereby the mold may be water-cooled and the bottom swung clear of the mold cavity to release a casting involve no 45 part of the invention herein sought to be pro-

tected and need not, therefore, be illustrated or described in detail.

An important feature of the invention consists in deeply recessing the mold bottom, as at 22, in such manner that a stream of metal poured into the mold through its open top in a direction such as to clear the side walls of the mold may fall into the approximate center of the recess 22 and very quickly accumulate a small pool or puddle of metal, so that before the surface of the molten 10 metal has risen through the bottom of the mold proper, a sufficient quantity of molten metal will have accumulated to receive the inflowing stream of metal without any further material degree of spattering, after which the pouring may be continued by maintaining a substantially vertical stream through the approximate central portion of the mold and clear of its side walls until the mold has been completely filled.

As a means of pouring metal in a substantially 20 vertical stream down the approximate center of the mold, a suitable implement such, for example, as a funnel 23, may be held below the spout 24 of the furnace or other reservoir 25, from which the molten metal is to be supplied, by an appropriate 25 movable supporting runway 26. The funnel may be mounted in a carriage 27 provided with rollers 28 by means of which it may be moved along the runway in one direction, and the runway may be pivotally connected with any available 30 means of support and provided with a handle 29 by which it may be swung about the axis O, O, Fig. 1, as indicated by broken lines 30—30, Fig. 2. The funnel 23 may be provided with a detachable 35 pouring spout 31, which may be selected from an assortment of spouts of different sizes, and by thus selecting a spout of proper size and by carefully adjusting the position of the funnel over the mold by moving the carriage along the runway and swinging the runway to the proper angular 40 position by means of the handle 29, a stream of any desired size may be directed vertically down the center of the mold, clear of its side walls, into the depression 22 at its bottom.

The funnel or other implement used as an aid 45 in directing the stream of metal from the furnace spout 24 into the mold and the specific means employed to support and adjust the position of such implement constitute no part of the invention to be claimed herein.

The mold cavity or matrix 20 may be of either 50 square or circular form in cross section and of proportions such as to be used in the casting of bars to be first rolled and then drawn in the process of making wire. To this end the matrix 55

should be inclined upwardly near its top, as at 32, and the recess 22 in the bottom 21 should be of a depth and degree of flare such as to localize the imperfections due to the initial part of the pouring when the stream of metal strikes the floor of the recess, to a small portion of the tapered lower end of the resulting casting, which may be cropped off at a level X, X, and at or near the upper end of its upper tapered portion, as at the level Y, Y, and leave a wire bar having both of its ends tapered in a form such as to facilitate the entrance of the bar between the rolls of a rolling mill.

When the depression in the bottom of the mold 15 is of a depth compared with its cross-sectional dimensions such as to render the swinging of the bottom of the mold clear of the mold cavity difficult without placing the axis of its hinged connection at a distance so far from the axis of 20 the mold cavity as to be impracticable, the bottom may be dropped from the mold with the casting and subsequently separated therefrom. Since the casting is at a higher temperature than the bottom when the casting is separated from 25 the mold, the casting will contract during cooling to a greater extent than will the bottom, so that no difficulty will be involved in separating the bottom from the end of the casting. The wall of the matrix may, if desired, as is usual 30 in molds for casting, be gently flared outwardly from the lower level of its upper tapered end portion 32 to the upper level of the bottom or door 21, but the degree of such flare should not be materially greater than is necessary to free- 35 ly release a cast ingot from the mold 20, when not supported by the said bottom or door.

The invention is not intended to be limited to the specific form of apparatus herein disclosed for purposes of illustration, but should be regarded as including modifications and variations thereof within the scope of the appended 5 claims.

What is claimed is:—

1. An open top, vertical mold, of a form adapted for use in the casting of copper wire bars, comprising copper castings united to form a matrix several diameters in length, with inwardly flaring upper and lower portions, the mold comprising sections separable along a dividing plane disposed transversely with respect to its longitudinal axis and lying between the parts thereof of which enclose the inwardly flaring portions of the matrix, the portions of the matrix of reduced cross-sectional dimensions being of lengths greater than the desired lengths of the tapered end portions of the wire bar to be cast, whereby the part cast in the upper end of the mold and the part cast in the bottom of the reduced portion of the matrix in which the initial pool of metal is formed at the commencement of the pouring of a casting, may be cropped off and leave a bar having tapered portions at its opposite ends.

2. A mold, as defined by claim 1, of which the transversely disposed plane along which the sections are separable is located at the level at which the lower flaring portion of the matrix merges with the portion lying between the two flaring portions.

WILLIAM F. EPPENSTEINER.
